CLAIM

I claim the ornamental design for a portion of truck cowl hood, as shown and described.

DESCRIPTION

FIG. 1 is a front perspective view of a portion of a truck cowl hood showing my new design;

FIG. 2 is a left side elevational view thereof, the right side being a mirror image thereof; and,

FIG. 3 is a top plan view thereof.

The portions of the hood shown in broken lines are for illustrative purposes only and form no part of the claimed design.
